CLAIM

The ornamental design for a T-shirt with a pocket, as shown and described.

DESCRIPTION

FIG. 1 is a front elevation of a T-shirt with a pocket showing my new design; and,

FIG. 2 is front elevation view of the pocket member shown on an enlarged scale and shaded to indicate transparency.

The broken lines shown in FIG. 1 are included for purposes of illustrating environment and form no part of the claimed design. The broken lines shown in FIG. 2 represent stitching.
